UNITED STATES PATENT OFFICE.

DANIEL SCHUYLER, OF LOS ANGELES, CALIFORNIA, ASSIGNOR TO THE
PERFECT SLIDING DOOR COMPANY, OF LOS ANGELES, CALIFORNIA,
A CORPORATION OF CALIFORNIA.

METHOD OF CONSTRUCTING POCKETS IN WALL STRUCTURES FOR SLIDING DOORS OR WINDOWS.

SPECIFICATION forming part of Letters Patent No. 690,081, dated December 31, 1901.

Application filed July 20, 1900. Received May 23, 1901. Serial No. 61,642. (No model.)

To all whom it may concern:

Be it known that I, DANIEL SCHUYLER, a citizen of the United States, formerly of San Diego, now of Los Angeles, in the county of 5 Los Angeles, State of California, have invented a new and useful Improvement in Wall Structures Pertaining to Pockets for Sliding Doors or Windows and Method of Constructing the Same, of which the following is a specification.

Although my invention in its more complete form is especially designed for forming the wall-pocket for sliding doors, the invention involves improvements applicable for the construction of other hollow walls and also for the construction of walls of a single thickness and also for the construction of ceilings.

The main object of my invention is to provide an improved form of wall-pocket for sliding doors to perfectly accommodate the sliding door in what is known as a "four-inch wall"—that is to say, a wall formed with two-by-four-inch studding.

By my invention I propose to provide a hollow wall of the dimensions stated and having a pocket-space of ample width for ordinary sliding doors of very great strength and durability, to avoid all danger of breaking away and falling down of plaster inside the pocket, 25 to provide smooth plastered surfaces inside the pocket over all of the surfaces, which in the ordinary construction would present bare laths, except when specially lined, and to secure all of these advantages by extremely 30 simple means and at less expense for material than is required in the old forms of structures.

In constructing my improved wall-pocket I provide for completely closing the pocket 40 throughout, except at the opening through which the door slides into the pocket, so that there will be no openings for vermin or for draftways in case of fire.

In the ordinary methods of plastering where 45 the plaster is in an integral body the plaster which is forced through the interstices in the lathing hangs upon the inside in the form of what are generally known as "clenchers" and which project at irregular distances. These 50 clenchers often extend so far into the space

behind the lathing that they interfere with the sliding of the door and are subject to be jarred off and to fall to the floor and to interfere at the base with the sliding of the door. Furthermore, the bond which is formed 55 by said clenchers, composed of the plaster which is squeezed through the interstices of the plastering upon laths which are fastened to the studding in the ordinary method, is very weak, for the reason that the plaster is not 60 brought into positive contact with the inner face of the lathing. This weakness of bond between the plaster and the lathing causes the plaster to be liable to become loose and in some instances to fall off in case the clenchers 65 become softened by moisture. The liability of the plaster to become loose and fall off results from the fact that the plaster does not fully fill the interstices between the lathing. This is more particularly true in the case 70 of wooden lathing.

By my method of plastering I produce a very strong bond between the plaster and the lathing and entirely cease with the plaster the portions of the lathing which are ordinarily exposed, and I can produce with wooden lathing fastened to studding a wall of greater 75 strength and which is much less liable to yield to destructive influences than walls heretofore made with like lathing. My invention, 80 however, is applicable to walls constructed with metal lathing.

By my invention I insure greater cleanliness by avoiding rough surfaces and projections for the lodgment of dust and other foreign matter. By completely covering the lathing and closing all cracks I make the wall 85 more vermin-proof than heretofore insured by the ordinary methods of plastering.

My newly-invented method of plastering 90 for forming wall-pockets and other plastered walls consists in supplying to one side of the lathing to be plastered, a form or backing at a slight distance from the lathing and then applying, in the usual way, the plaster to the 95 opposite side of the lathing in the form of mortar, and pressing the same through the interstices between the lathing thus filling the space between the lathing and the form or backing, to produce between the lathing and 100

the form or backing an integral body of plaster corresponding to the body of plaster on the face of the wall outside the lathing. Sufficient pressure is applied in forcing the mortar through the interstices to produce a hydrostatic pressure in the space behind the lathing to bring all the mortar into intimate contact with the lathing on the rear side thereof and in the interstices and to form a strong bond between the lathing and plaster all around the exposed portions of the lathing—that is to say, the plaster is forced into intimate contact with the entire face of the lathing except that portion which is in direct contact with the studding. The pressure ordinarily applied in the former mode of plastering is sufficient to produce the required effect when the backing is in place to confine the mortar and produce the required hydrostatic pressure. The space to be left between the backing and the lathing may be of greater or less width, according to the preference of the builder; but it can be of such width that the quantity of plaster required to fill it will not exceed that ordinarily required to form the so-called "clenchers" and to supply the waste which breaks off and falls inside the wall in the former method of plastering walls formed with lathing fastened in the wall.

I prefer that the form or backing presented to the plastering be as smooth as possible, and I propose to make the same of wood and to oil the surface of the wood which comes into contact with the plaster, thus to prevent the plaster from sticking to the form; but it may be made of metal or any other suitable material.

In constructing the wall-pocket I prefer for economy to use a form or backing having panels to fit into the spaces between the members of the wall which serve the purpose of studding and bracing the wall.

In carrying out my invention the frame of the structure is constructed with a view to being readily produced at the lumber-mill and can be shipped in set-up or knocked-down form and can be erected in the building with great accuracy, ease, and readiness.

In my invention I form the plaster in an integral body enveloping the lathing and formed in a substantially unbroken face on the side opposite the studding and extending on the other side with substantially unbroken face from studding to studding—that is to say, I produce with the plaster a finished surface upon both sides of the lathing in a substantially unbroken face from the top to the bottom of the wall.

My invention also includes the specific form of structure for the wall and sliding-door pocket.

The accompanying drawings illustrate my invention.

Figure I is a fragmental perspective view showing my improvement in course of erection into a building, the floor and the ceiling joists of which are partially shown. Differ-

ent parts of the wall structure are shown in different stages of completion. Fig. II is an elevation of my wall structure applied with a door in place. Dotted lines indicate the hidden framing. Fig. III is a vertical section on line III III, Figs. V and VI, omitting the form or backing for molding the plaster inside the pocket. Fig. IV is an enlarged plan section on line IV V, Fig. II, with the form in place applying the mortar. Fig. V is a like section after the forms have been withdrawn. Fig. VI is an enlarged plan section on line VI VI, Fig. III. Fig. VII is an enlarged vertical section on line VII VII, Fig. III. Fig. VIII is an enlarged section on line VIII VIII, Fig. III.

a indicates the base upon which the wall stands. This may be any suitable support such, for instance, as a floor. *b* indicates the top support for the wall. This may consist of one or more joists of the ceiling.

It is to be understood that the wall may extend parallel with the ceiling-joists as well as across them. In the drawings the wall is shown as extending crosswise of the ceiling-joists *b*.

c indicates a cross-studding for the end of the door-pocket and resting on the base and extending to and fastened to the top support on joist *b* and being of a width to extend fully across the space between the lathing of the wall. This studding is preferably a two-by-four-inch studding.

d d' indicate two door-post studding, oblong in cross-section, resting on the base *a* and extending to and fastened to a plate or header *j* at the top of the door-pocket and set equidistant from the cross-studding *c*, with their greater widths parallel with each other and with their outer faces in the plane of the outer face of the plastering of the proposed wall. Said studding is preferably two-by-four-inch studding rabbeted to form recesses *l l'*, respectively, in their outer faces at the edges which face toward the cross-studding, faces of said recesses and the other studding being in one plane and the lathing being fastened on said faces—that is to say, the rabbets are equal in depth to the depth of wall from the outside face of the plaster to the inside face of the lathing *e e'*, so that the lathing can be seated on the cross-studding and in the rabbets of the door-post studding.

f f' indicate supplemental intermediate studdings substantially corresponding in thickness to the rabbet-tongues *g g'*, respectively, and extending from base to header-plate *j* between the cross-studding and the rabbeted studding on opposite sides of the wall-pocket to support the lathing intermediately. *e* indicates the lathing fastened to the outer face *2* of one of said tongues *g* and extending to and fastened to the corresponding outer face *3* of the cross-studding *c* and also fastened to the outer face of the intermediate studding *f*. *4* indicates an integral body of plaster substantially enveloping the lathing and formed

in a substantially unbroken face 5 on the side opposite the studding and extending on the other side of said integral body in a smooth substantially unbroken face 6 from studding 5 to studding. e' indicates lathing on the outer face 2' of the other tongue g' and outer face 3' of the cross-studding. 5' indicates plaster substantially enveloping said lathing 4' and formed in a substantially unbroken face on 10 the side opposite the studding and extending on the other side with a substantially unbroken face 6' from base to plate.

h h' respectively indicate horizontal bars fastened to the cross-studding c and rabbeted 15 studding d d', respectively, and also fastened to the supplemental studding f f', respectively.

i indicates a studding for the door-post resting on and fastened to the post a and fastened to the top support b.

j indicates the header which forms the top of the pocket. The header j extends from the door-post studding i to the cross-studding c, which forms the end of the pocket and is 25 fastened thereto.

7 indicates gains cut in the wider faces of the several studding to seat the header j.

k indicates studding extensions extending up from the header j to the top-support joists 30 b to form extensions of the studding d d' and of the studding f f'. The studding extensions k are respectively provided with tenons 8, which rest on the header j and fit between upwardly-projecting portions 9 of the studding d d' f f', which project above the top of the header j. Above their tenons the studding k are of the same width as the studding i and c and are set with their greatest width across the wall to correspond with the studding c and i. The ends of the tenons 8 rest on the header j, and the shoulders 9 on each side of the tenons 8 rest on the tops of the studding d d' and f f'. The several studdings will be fastened to the header and top support and to the base by any suitable means, 45 such as the nails n.

I will now describe the method of constructing my newly-invented wall structure as applied for the wall-pocket of a door.

50 The studding i c, d d', f f', and k k' and the header j and the bracing-bars h h' will be cut at the mill exactly as required in the building, and, if desired, they may be fitted together at the mill and strips (not shown) 55 tacked to the free ends of the several studding to prevent any racking of the parts in transportation. Then the structure will be taken to the building where it is to be set up, or, if preferred, the parts can be cut to size at 60 the mill and then transported to the building before being assembled. The frame formed of the studding and bars will then be erected in place and the lathing e e', of any suitable character, will be applied, providing suitable 65 interstices r, and their ends being set in the gains l l' and fastened to the tongues g g', respectively, and also to the studding c and

f f'. The framework formed by the studding and bars, with lathing fastened to the studding by nails in the ordinary way, having 70 thus been furnished, the workmen will then apply within the wall and at a short distance—say a half-inch, more or less—from the lathing one or more plates p, having a substantially smooth surface to sustain the pressure 75 of the plastic mortar to be forced through the interstices of the lathing. These plates when applied in the wall-pocket will rest against the inner faces of the door-post studding and intermediate studding, and each plate will be 80 held by a wedge q, which fits between the plate p and the studding on the opposite side of the pocket. Then the plaster will be applied to the lathing upon the outer face of the wall, pressure being applied in the usual manner to force the plaster through the interstices of the lathing, and to mold the same against the face of the plates p and to force the plaster into close bond with the entire exposed surface of the lath, thus to fully envelop 85 the lath and apply the plaster under pressure to all exposed faces of the lathing. After the plaster has been applied to the wall in front of the plate or plates said plate or plates will be removed and the plaster allowed to set in 90 the ordinary way. The wall thus formed will present a smooth plastered surface on both sides of the lathing.

The plates are preferably of metal, but may be made of wood. In order to avoid any liability of sticking and also to produce a superior surface on the inner face of the plaster, the face of the plate if made of wood should be kept well oiled.

The door-post studding d and d' are set at 105 the distance apart necessary to accommodate a door of the required thickness and said studding arranged, as shown, from a strong door-post and being fastened at top and bottom to the heading and base a gives great 110 strength to the wall. The door-post studding i and the cross end studding c being fastened to the top support and base give greater strength and stability to the wall than would be given if said studding did not extend to 115 the joists. The rabbets l l' in the studding d d' are equal in depth to the thickness of the plastered wall from the inside face of the lathing to the outside face of the plaster, so that when the door-casing is placed on the outer 120 faces of the studding d d' it will fit close upon the face of the plaster.

My new method of plastering may be applied to other walls and to ceilings.

The lathing may be of wood or metal, as preferred by the builder.

The plaster between the studding on the side of the lathing which faces the studding forms a solid body tightly set between and molded onto the studding. This materially 130 increases the strength and rigidity of the wall and is of much value where a thin wall is required. While the advantage of this construction is of special importance in the con-

struction of wall-pockets for sliding doors, I do not propose to limit its use to the construction of wall-pockets. Wherever my invention is applied, whether in ceiling or wall, 5 the plaster will act as a brace between the timbers which support the lathing. In applying the plaster to ceilings the former or backing will be upheld between the joists above the lathing by blocks, (not shown,) 10 which will be laid on the lathing to afford a space for the plaster between the lathing and the backing in the same way as with the intermediate studding *f*' and the studding *a*'.

What I claim, and desire to secure by Letters Patent of the United States, is—

1. A wall comprising a base; a header; a studding fastened to and extending between the base and the header and extending transversely across the space between said base 20 and header; studding connecting the base and header and oppositely arranged to provide an open space extending along and between the inner faces of the base and header; lathing on the studding on one side of the 25 open space; an integral body of plaster enveloping said lathing and formed in a substantially unbroken face on the side opposite the studding and extending on the other side in a substantially unbroken face from 30 studding to studding; lathing on the studding on the other side of said open space; and an integral body of plaster enveloping such lathing and formed in a substantially unbroken face on the side opposite the studding and extending on the other side in a substantially unbroken face from studding to 35 studding.

2. A wall comprising a studding rabbeted at one edge; other studding corresponding in 40 thickness to the tongue formed by the rabbet; a base and a header holding said studding with one face in line with the rabbet-face of said tongue; lathing of less depth than said rabbet, fastened in said rabbet and against 45 said studding; and an integral body of plaster in said rabbet and extending in a substantially unbroken face in front of said lathing and extending through the interstices of the lathing and formed in a substantially unbroken face on the other side of the lathing 50 from studding to studding.

3. The combination of a base; a header; a cross-studding connecting the base and header and of a width to extend across the space between the lathing of the wall; two studding oblong in cross-section connecting the base and header and set equidistant from the cross-studding with their greater widths parallel with each other and with their outer faces in 55 the plane of the face of the proposed wall; said studding being rabbeted at their outer faces at the edges which face said cross-studding; the outer faces of the tongues formed by said rabbets being in the plane of the outer faces of said cross-studding; lathing fastened to the outer face of one of said tongues and extending to and fastened to the corresponding outer face of the cross-studding; a body of plaster on said lathing; lathing on the 60 other tongue and outer face of the cross-studding; and plaster on said lathing.

ing outer face of the cross-studding; an integral body of plaster substantially enveloping the lathing and formed in a substantially unbroken face on the side opposite the studding and extending on the other side in a substantially unbroken face from studding to studding; lathing on the other tongue and outer face of the cross-studding; and plaster substantially enveloping said lathing and formed in a substantially unbroken face on the side opposite the studding and extending on the other side with substantially unbroken face from studding to studding.

4. The combination with a base and a top support, of a door-post studding fastened to the base and extending to and fastened to the top support; the pocket end studding fastened to the base and extending to and fastened to the top support; a header extending between and fastened to the pocket end post and the door-post; two pocket-mouth posts set flatwise on opposite sides of the header and fastened to the header and to the base, and rabbeted on their outer faces at the edge next the pocket end post; two intermediate studding respectively fastened to the base and to the header on opposite sides thereof, the outer faces of said intermediate studding being in 95 the plane of the outer faces respectively of the rabbet-tongues and cross-studding; lathing on the outer faces of said tongues and studding; and plaster on said lathing.

5. A wall comprising a studding rabbeted at one edge; other studding corresponding in thickness to the tongue formed by the rabbet; a base and header holding said studding with one face in line with the rabbet-face of said tongue; lathing fastened in said rabbet 105 against said studding; and a body of plaster in said rabbet and on said lathing.

6. The combination of a base; a header; a cross-studding connecting the base and header and of a width to extend across the space between the lathing of the wall; two studding oblong in cross-section connecting the base and header and set equidistant from the cross-studding with their greater widths parallel with each other and with their outer faces in 110 the plane of the face of the proposed wall; said studding being rabbeted at their outer faces at the edges which face said cross-studding; the outer faces of the tongues formed by said rabbets being in the plane of the outer faces of said cross-studding; lathing fastened to the outer face of one of said tongues and extending to and fastened to the corresponding outer face of the cross-studding; a body of plaster on said lathing; lathing on the 115 other tongue and outer face of the cross-studding; and plaster on said lathing.

7. A wall-section comprising a studding, a recess being provided at one edge thereof; other studding; faces of the recess and the 120 other studding being in one plane; lathing on said faces; a base and header holding said studding; and a body of plaster in said recess and on said lathing.

8. A wall-section comprising a studding, a recess being provided at one edge thereof; other studding; faces of the recess and the other studding being in one plane; lathing 5 on said faces; means for supporting the studding; and a body of plaster in said recess and on said lathing and enveloping the lathing between the studding.

9. A wall-section comprising a studding, a 10 recess being provided at one edge thereof; other studding; faces of the recess and the studding being in one plane; lathing on said faces; means for holding said studding; and a body of plaster enveloping said lathing be- 15 tween said studding.

10. A wall composed of two parallel sections connected together at the top, bottom and one edge, and with an open space at the other edge between said sections to form a 20 pocket open at one edge and closed at the other edge and at top and bottom, inner faces

of both of said sections being coated with plaster.

11. A wall composed of two parallel sections connected together at the top, bottom 25 and one edge and with an open space at the other edge and between said sections to form a pocket open at one edge and closed at the other edge and at top and bottom; said sections being respectively formed of studding 30 and lathing, and plastering covering the lathing and enveloping the lathing between the studding.

In testimony whereof I have signed my name to this specification, in the presence of 35 two subscribing witnesses, at Los Angeles, California, this 9th day of July, 1900.

DANIEL SCHUYLER.
